H. A. TUCKEY,
SIGNAL AND ILLUMINATOR FOR AUTOMOBILE RADIATOR INDICATORS,
APPLICATION FILED AUG. 9, 1921.
1,431,065. Patented Oct. 3, 1922.

Inventor:
H. A. Tuckey.

UNITED STATES PATENT OFFICE.

HARRY A. TUCKEY, OF SAN FRANCISCO, CALIFORNIA.

SIGNAL AND ILLUMINATOR FOR AUTOMOBILE RADIATOR INDICATORS.

Application filed August 9, 1921. Serial No. 491,052.

To all whom it may concern:

Be it known that I, HARRY ALFRED TUCKEY, a citizen of the United States, residing at the city and county of San Francisco and State of California, have invented certain new and useful Improvements in Signals and Illuminators for Automobile Radiator Indicators, of which the following is a specification.

10 Devices for indicating the temperature of the water in a motor vehicle cooling system, particularly that type of device associated with the radiator filler cap, are plainly readable during the day, but at 15 night without the aid of a portable lamp a vehicle operator is unable to read the temperature of the water in the cooling system.

To maintain the successful and economical operation of a motor vehicle, it has been 20 found necessary to maintain the motor temperature approximating a certain degree during day driving as well as night driving, and it is the object of the present invention to provide a means associated 25 with the temperature indicator enabling the reading of the indicating element thereof in the dark.

Another object of this invention is to utilize the present form of universally used indicating device, and to provide a simple attachment adapted for easy application thereto, at comparatively little cost, and preferably by dispensing with the rear plate associated with the indicator frame.

35 A further object is to provide in connection with the present invention a signal for intersecting traffic i. e. traffic traveling across the path of the vehicle by providing illuminated signals in color, one facing in 40 each direction at the forward end of the vehicle indicating to cross traffic by lights whether the equipped vehicle will proceed or whether the cross traffic vehicle shall proceed.

45 With the above mentioned and other objects in view, the invention consists in the novel construction and combination of parts hereinafter described, illustrated in the accompanying drawings, and set forth in the 50 claims hereto appended, it being understood that various changes in the form, proportion, size and minor details of construction within the scope of the claims may be resorted to without departing from the spirit 55 or sacrificing any of the advantages of the invention.

To more fully comprehend the invention reference is directed to the accompanying drawings, wherein:—

Figure 1 is a view in side elevation of the 60 preferred embodiment of my invention.

Figure 2 is a vertical central section disclosing the preferred embodiment of my invention.

Figure 3 is a transverse broken sectional 65 view through the lamp chamber.

In the drawing wherein like characters of reference designate corresponding parts, 1 indicates the metallic attaching portion of a radiator cap mounting the exterior finishing portion 2, both of which are provided with the aligned stem receiving openings 3 into and through which projects the threaded stem 4 of the well known type of motor temperature indicating device held 75 in position by a nut 5. The stem 4 carries a circular frame portion 6 open at its front and rear, the front, or that face disposed toward the vehicle operator being normally closed by a crystal 7 held in position by a removable ring 8. In the form illustrated, the temperature indicating means is in the form of a closed tube 9 disposed vertically of the frame 6 with its lower end 10 protected by a shell 11 extending below the 85 member 1. The member 9 contains a temperature responsive fluid in the tubular portion 12 thereof, and in rear of said tube is a suitable indicating disk 13 having a vertical sight opening 14 therein immediately in rear of said tube 9 and of a length substantially corresponding to that portion of the tube between the inner edges of the frame 6. This present construction, which is of the conventional form, is that used 95 with certain other features closing the rear of the frame at the present time, and the preferred embodiment of applicant's invention is associated therewith in the hereinafter described manner.

To the rear portion of the frame 6 is attached in any suitable manner by attaching means, not shown the annular flanged portion 16 of a suitable lamp casing 17. The casing is provided with an enlarged lamp chamber 18 forwardly from which extends the contracted passage 19 communicating with the rear of the sight opening 14, and in said chamber 18 is adapted for positioning an electric lamp 20 of any well known form mounted in the conventional socket 21, and adapted to be supplied with power 105 110

through a contact device 22 for connection with the power source, not shown.

The side walls of the lamp chamber, which are disposed in parallel vertical sections at right angles to the plane of the frame 6, are formed with suitable openings 23, in each of which is adapted to be removably mounted a colored translucent closure 24 affording a signal. The member 24 over the opening 23 disposed at the side of the vehicle corresponding with the right hand of the driver is adapted to be blue or green denoting the right of way for a vehicle approaching from that side, while the member 24 associated with the opposite opening is adapted to be red denoting the danger or stop signal for a vehicle approaching from that side.

Thus it will be apparent that during night driving, my present invention affords a signal for traffic at intersecting streets, and also affords a means for illuminating the tube 9 by rays passing through the sight opening 14 whereby the indicating element in the tube may be readily read by the driver.

If desired, a brace 25 may extend from the portion 4 to the socket portion 26 associated with the contact 22.

It will be apparent that the present invention is adapted for attachment to the well known forms of moto-meters, now universally in use, by simply removing the back plate from the frame thereof inserting a new indicating disk formed with a sight opening extending the full length of the tube 9 and attaching my improved lamp chamber to the rear of the frame. This construction provides a mounting which is adapted to be removed with the moto-meter and radiator cap as a unit from the radiator.

Having thus described my invention, what I claim as new and desire to secure by Letters Patent of the United States is:—

1. In combination with an instrument for mounting on an automobile radiator and consisting of a frame, a movable indicating means influenced by varying indicating temperatures of water in the radiator, a dial formed with a sight opening; of means in

rear of said dial for illuminating the movable indicating means enabling the reading of said means through the sight opening in the dark, the same consisting of a lamp chamber having a passage for registering with the sight opening and side wall openings, a lamp within said chamber, a mounting plate associated with said chamber for detachably securing the chamber to the frame in the rear of said dial plate and translucent members associated with the said side wall openings for closing the same.

2. In combination with an instrument for mounting on an automobile radiator and consisting of a frame, a movable indicating means influenced by varying indicating temperatures of water in the radiator, a dial formed with a sight opening and a crystal in front of the dial; of means in rear of said dial for illuminating the movable indicating means enabling the reading of said means through the sight opening in the dark, the same consisting of a metallic lamp chamber having an opening in one wall for registering with the sight opening and an opening in each side wall, a lamp in said chamber at the intersection of said openings, a red transparent member over one side wall opening, a green transparent member over the other side wall opening, and a mounting plate integral with and flaring from the walls of said chamber for detachably securing the chamber to the frame in the rear of said dial.

3. A device for the described purpose comprising a walled lamp chamber open at its sides and one end, the wall at its open end terminating in an annular attaching disk integral therewith and radiating from said open end for attaching to the rear of a radiator thermometer frame to horizontally dispose said lamp chamber relatively thereto, said chamber side wall openings adapted for closing by translucent members and a lamp within said chamber.

In testimony whereof I have signed my name to this specification.

HARRY A. TUCKEY.
